UNITED STATES PATENT OFFICE.

FRANK J. RAUCHUT, OF PHILADELPHIA, PENNSYLVANIA.

BROOM AND MOP HOLDER.

Application filed June 23, 1923. Serial No. 647,327.

To all whom it may concern:

Be it known that I, FRANK J. RAUCHUT, a citizen of the United States, residing at Philadelphia, in the county of Philadelphia and State of Pennsylvania, have invented new and useful Improvements in Broom and Mop Holders, of which the following is a specification.

The invention relates to a broom and 10 mop holder.

The object of the present invention is to provide a simple, practical and efficient broom and mop holder designed for household use and adapted to be cheaply manufactured and capable of enabling the handles of mops and brooms and the like to be readily engaged with it and disengaged from it so that the mop or broom may be easily and quickly placed in the rack when 20 not in use and readily removed therefrom for use.

With these and other objects in view the invention consists in the construction and novel combination and arrangement of 25 parts hereinafter fully described, illustrated in the accompanying drawing and pointed out in the claim hereto appended, it being understood that various changes in the form, proportion and minor details of construction, within the scope of the claims, 30 may be resorted to without departing from the spirit or sacrificing any of the advantages of the invention.

In the drawing, in which like characters 35 of reference designate corresponding parts in the several views:—

Figure 1 is a perspective view of a broom and mop holder constructed in accordance with this invention.

Figure 2 is a vertical longitudinal sectional view of the same, illustrating the manner of supporting a broom and a mop.

In the accompanying drawing, in which is illustrated the preferred embodiment of 45 the invention, the combined broom and mop holder comprises in its construction a vertical backboard 1, vertical end blocks 2, a central triangular block 3 and a front board 4. The backboard is of oblong shape and

50 the end blocks 2, which are suitably secured to the front face of the backboard project forward therefrom and form end abutments for rollers 5 and for handles 6 and 7 of a broom and a mop or the like. The end blocks have their upper and lower ends 55 and their outer side faces in flush relation

with the edges of the backboard and the triangular block 3, which is arranged centrally of the backboard and suitably secured to the same, is of a thickness less than the thickness of the end blocks in order that the front board 4 may be arranged against the central triangular block in substantially flush relation with the front faces of the end blocks and with its upper and lower edges in the planes of the upper and lower edges of the backboard. The front board 4 is rectangular and its lower edge is coincident with the base of the triangular block, while its upper corners project from the sides of the triangular block. The upper edge of the front board is arranged in the same plane as the apex of the central triangular block and the upper edge of the backboard. The side edges of the central front board are arranged in spaced relation with the inner side faces of the end blocks to provide openings or spaces to permit the handles 6 and 7 to be readily introduced into and removed from the device. The 80 clamping rollers 5, which are horizontal, are of a diameter greater than the distance between the base of the triangular block 3 and the lower ends of the end blocks 2, in order that the central front board will retain the loose clamping rollers in the space between the central and end blocks.

The handles 6 and 7 fit against the inner vertical faces of the end blocks and the clamping rollers, which engage the handles, 90 roll on the inclined sides of the triangular block and are adapted to securely hold the handles in the device. A slight upward movement of either handle will release the same and enable the broom or mop to be 95 readily removed from the holder.

The holder is provided with suitable hangers 8, which are shown in the form of screw eyes for enabling the device to be readily hung against a wall, and the holder 100 is also provided at the front and ends with central and side supporting hooks 9 and 10, but the supporting hooks and the hangers may be of any desired construction, as may be readily understood.

It will be seen that the broom and mop holder presents a neat and attractive appearance and that it is particularly adapted for household use for serving as a rack for holding a broom and mop.

What is claimed is:—

A combined broom and mop holder, com-

prising a vertical backboard, vertical end blocks secured to the backboard and projecting forwardly therefrom and presenting inner vertical abutment faces, a central triangular block secured to the backboard and being of a thickness less than the distance between the front and rear faces of the blocks, a central front rectangular shaped board secured to the front face of the triangular block in substantially flush relation with the front faces of the end blocks and arranged in spaced relation to the said end blocks to provide open-ended, spaced passages between said vertical end blocks, for the handles of a broom and mop, said

front board being substantially coincident with the base of the triangular block and projecting from the inclined sides thereof, and horizontal clamping rollers confined by the central front board in the spaced passages between the triangular and end blocks and arranged to roll downwardly and convergingly with relation to each other on the inclined sides of the triangular block for clamping the handles of a broom and mop against the inner vertical faces of the end blocks.

In testimony whereof I have hereunto set my hand.

FRANK J. RAUCHUT.
